in which a mobile terminal is provided in broken lines to illustrate an example environment.

(56) **References Cited**

The appearance of the transitional image sequentially transitions between the images shown in FIGS. 1 through 4. The subject matter of this patent includes a process or period in which an image changes into another image. This process or period forms no part of the claimed design. The broken line drawing of the mobile terminal, and the text, number, symbol and otherwise images shown in broken lines in the graphical user interface of FIGS. 1 through 5 are for illustrative purposes only and form no part of the claimed design.
